UNITED STATES PATENT OFFICE

146,162

DESIGN FOR AN AIRPLANE

Robert J. Woods, Grand Island, N. Y., assignor to
Bell Aircraft Corporation, Wheatfield, N. Y.

Application October 27, 1945, Serial No. 123,243

Term of patent 14 years

(Cl. D71—1)

To all whom it may concern:

Be it known that I, Robert J. Woods, a citizen of the United States, residing at Grand Island, in the county of Erie and State of New York, have invented a new, original, and ornamental Design for an Airplane, of which the following is a specification, reference being had to the accompanying drawings, forming part thereof.

Fig. 1 is a top plan view of an airplane showing my novel design;

Fig. 2 is a diagrammatic outline of a sectional view taken along line II—II of Fig. 1;

Fig. 3 is a diagrammatic outline of a sectional view taken along line III—III of Fig. 1;

Fig. 4 is a front end elevational view thereof;
Fig. 5 is a rear end elevational view;
Fig. 6 is a side elevational view thereof; and
Fig. 7 is a fragmentary bottom plan thereof.
The characteristic features of my design reside in the portions shown by means of full lines in the drawings.

I claim:

The ornamental design for an airplane, as shown and described.

ROBERT J. WOODS.
